UNITED STATES PATENT OFFICE.

HENRY J. HARDENBERGH, OF NEW YORK, N. Y., AND GUSTAV A. WEINREICH, OF PHILADELPHIA, PENNSYLVANIA; SAID WEINREICH ASSIGNOR TO SAID HARDENBERGH.

TRANSOM-LIFTER.

SPECIFICATION forming part of Letters Patent No. 285,811, dated October 2, 1883.

Application filed June 19, 1883. (Model.)

To all whom it may concern:

Be it known that we, HENRY J. HARDENBERGH and GUSTAV ARNO WEINREICH, citizens of the United States, residing in the city, 5 county, and State of New York, and in the city and county of Philadelphia, and State of Pennsylvania, respectively, have invented certain new and useful Improvements in Transom-Adjusters; and we do hereby declare the following to be a full, clear, and exact description of the invention, such as will enable others skilled in the art to which it appertains to make and use the same, reference being had to the accompanying drawings, and to letters 15 of reference marked thereon, which form a part of this specification.

The object of the invention is to produce a simple and efficient device for adjusting transoms.

20 The invention consists in the combination and arrangements of parts, substantially as will be hereinafter set forth, and finally embodied in the claims.

25 Referring to the accompanying drawings, in which similar letters of reference indicate like parts in each of the several figures, Figure 1 is a front elevation of a portion of a transom, partially broken away to show the arrangement of the adjuster therein. Fig. 2 is a plan 30 or face view of the adjuster, showing the arrangement of the parts thereof, the operating mechanism being adapted to lie, preferably, in a recess formed in the edge of the transom, and concealed from view by the plate *a*. Fig. 35 3 is a section taken through line *x*.

In carrying out our invention we secure upon the bed-plate *a*, which may be rounded on its lower end, as at *b*, for a purpose hereinafter given, a bolt, *c*, having a T-shaped head, *d*, 40 in which is formed a slot, *e*, to receive the fulcrumal pivot *g*, and to allow a sliding longitudinal movement to the bolt. Upon the lower extremity of the bolt is formed a pawl, *f*, adapted to engage with a ratchet-wheel, *h*, arranged to have a fixed or stationary relation to the door-jamb or part upon which the transom is hung.

In connection with the bolt *c* is employed a spring, *k*—preferably a coil-spring—arranged

around the bolt, adapted to automatically cause 50 the bolt-pawl to engage with the ratchet. Said coil-spring may bear on the shoulder *l* of the bolt and against the lugs or projections *m* on the bed-plate; or other arrangements of the spring may be made to produce the same result. 55

Upon the fulcrumal pivot *g* is arranged the lever *n*, which is provided with bearings *o* (shown in outline in Fig. 2) on each side of the fulcrum *g*, so that by raising or lowering 60 the projecting extremity of the lever, one of said bearings engages with one of the projections of the T-shaped head, and the bolt is raised from holding contact with the ratchet.

The arrangement of the ratchet-teeth and 65 pawl-arms is such as that when the two are in engagement the transom will be prevented from swinging in either direction.

The ratchet-wheel provides a bearing or journal, *p*, Fig. 3, upon which the bed-plate 70 secured to the transom revolves, said ratchet-wheel remaining stationary, as before stated, being carried by a plate, *q*, having an angular stud, *r*, thereon which passes into a correspondingly-angular aperture in the ratchet, as 75 shown in Fig. 3, and in outline in Fig. 2.

In operation, when the parts are arranged in their relative positions upon the transom and door-frame, the lever may be pulled downward by a cord, by which action the bolt is 80 drawn up and the pawl disengaged from the ratchet-wheel, thus allowing the transom to be opened. By pushing the lever with a cane or a rod the same action will result and the transom be closed, the spring causing the parts to 85 lock when the power is removed from the lever.

It is not necessary that the pivotal portions of the device be in the center of the transom, as, by means of my improvements, the said transom may be pivoted at or near either the 90 upper or lower edge of the same, the plate *a* at its upper or lower extremity being rounded to allow a pivotal movement thereof, as will be understood.

Having thus described our invention, what 95 we claim is—

1. In a transom-adjuster, the combination, with a stud secured to a stationary part on which

the ratchet is fixed, and a bed-plate secured to the transom on which the ratchet is journaled, of said ratchet, a bolt engaging therewith having a **T**-shaped head, and a pivoted lever having bearings under each side of the **T**-head to engage therewith, as set forth.

2. The combination of the ratchet-wheel, an angular stud in the door-jamb on which the ratchet-wheel is fixed, the bed-plate *a*, secured to the transom provided with an opening in which the ratchet is journaled, the sliding bolt held upon the plate *a*, a spring, *K*, for holding the bolt normally in engagement with the ratchet, and a lever, *n*, projecting outward

from the transom by which the bolt is operated, 15 as set forth.

In testimony that we claim the foregoing we have hereunto set our hands this 7th day of June, 1883.

H. J. HARDENBERGH.
GUSTAV ARNO WEINREICH.

Witnesses as to H. J. Hardenbergh:

HENRY S. MUEN,
W. C. HUNTING.

Witnesses as to Gustav Arno Weinreich:

CHARLES H. PELL,
F. F. CAMPBELL.
